UNITED STATES PATENT OFFICE.

CHARLES HANSEN, OF CORVALLIS, OREGON.

RULE.

No. 922,580.

Specification of Letters Patent.

Patented May 25, 1909.

Application filed October 20, 1908. Serial No. 458,645.

To all whom it may concern:

Be it known that I, CHARLES HANSEN, a citizen of the United States of America, residing at Corvallis, in the county of Benton 5 and State of Oregon, have invented certain new and useful Improvements in Rules, of which the following is a specification.

My invention while applicable to any rule, I have shown applied to an ordinary "two 10 foot" or carpenter's rule, and the object of my invention is to construct in a rule a part which may be used as a protector for the fingers or hand when using the rule as a gage, and which will not interfere in the slightest 15 degree with the use of the rule as a measure.

In order that my invention may be fully understood I will proceed to describe it with reference to the accompanying drawings, in which:

20 Figure 1 is a side elevation of a portion of a rule provided with my improvement. Fig. 2 is a plan of the same. Fig. 3 is a vertical section on the line 3—3, of Fig. 2. Fig. 4 is a side elevation showing the manner of using 25 the rule as a gage. Fig. 5 is a detail of the protector or pivoted sliding block.

My invention consists essentially in providing one or both end sections of an ordinary carpenter's rule, or, in the case of an 30 ordinary ruler, some portion thereof, with a long narrow slot with grooves in its sides, wherein is trunnioned a pivoted block, slideable toward either end, which block when not in use lies flush with the surfaces of the rule 35 or ruler, being removably held so by means of an upstruck catch, and which block when in use projects at an angle to the surface of the rule, is adjustable back and forth in the longitudinal slot, and serves as a rubbing block 40 between the fingers or hand and the material upon which a mark or other operation is to be made.

45 1 is an end section of a rule, formed preferably of wood or metal, and hinged to the adjacent section of the rule at 2.

3 is a block, formed preferably of metal, pivotally and slidably mounted in the section 1, by means of trunnions 4 projecting from block 3 into the long recesses or grooves 5, 50 formed in the sides of the long slot 1^a, the block 3 being retained in flush position, when not in use, by the struck up projections 6, which are formed on one or more corners of the block 3, lying within the grooves 5 and 55 abutting against the upper and lower sides of the grooves 5. These struck up projections

6, which may be mere burs made by tapping at 7 with an ordinary punch, may be compensated for by additional punching at any time, in case of their wearing away by frequent use. 60

The natural spring of the sides 1^b of the section 1 will permit the aforesaid projections to pass from their position in the grooves 5, past the sides 1^b, to a position 65 above or below the surface of the section 1, permitting the block 3 to rotate on its trunnions 4 to a position at an angle to the surface of the section 1, the ends of the block projecting above and below, as shown in 70 Fig. 3 in dotted lines and in Fig. 4 in full lines, where it is shown as pushed against the edge of plank 8, shielding from the surface of the plank, thumb 9 and forefinger 10, which, by reason of their gripping section 1, 75 serve as a stop to limit the movement of block 3, while the rule, acting as a gage, is moved along the plank, guiding pencil 11, in making a line parallel with the edge of the plank, for purposes well known to mechanics. 80

The trunnions 4 may be formed on the block 3 or may be made of a short section of wire passed through the block. Owing to the flat sides of the block 3 its movement is confined to a sliding and pivoted one in 85 but two planes, thus preventing the trunnions from turning to a position free of the grooves 5 and misplacing the block 3, which, in the manufacture of the improvement, may be slipped in from one end prior to the riveting of the side pieces 1^b to the end piece as is done in the manufacture of some rules, or to each other as in other rules, or in any other practical manner. 90

It will be seen that the above described 95 device furnishes a simple and ready gage in a rule, without the slightest interference with the ordinary use of the rule, permitting it to be folded up flat, the pivoted block, in case it should not have been pushed flush by the 100 fingers, readily slipping into flush position on the folding up of the rule, the adjacent section of which will press the block into place.

Having thus described my invention, the following is what I claim as new therein, 105 and desire to secure by Letters Patent.

1. A rule having a slot, grooves in the walls of the slot, and a pivoted gage-block adapted to slide in the slot and provided with trunnions adapted to slide in the 110 grooves.

2. A rule having a longitudinal slot, grooves

in the walls of the slot, and a pivoted gage-block adapted to slide in the longitudinal slot and provided with trunnions adapted to slide in the grooves.

5. 3. A rule having a slot, grooves in the walls of the slot, and a pivoted gage-block adapted to slide in the slot and provided with trun-

nions adapted to slide in the grooves, and a projection providing a catch adapted to engage in a groove.

CHARLES HANSEN.
